R. C. ZANNOOTH

DRAIN FIXTURE

Filed Oct. 5, 1925

INVENTOR
ROBERT C. ZANNOOTH.
BY *Ralph H. W. Brown*
ATTORNEY

UNITED STATES PATENT OFFICE.

ROBERT C. ZANNOOTH, OF MILWAUKEE, WISCONSIN, ASSIGNOR TO ROBERTS BRASS COMPANY, OF MILWAUKEE, WISCONSIN, A CORPORATION OF WISCONSIN.

DRAIN FIXTURE.

Application filed October 5, 1925. Serial No. 60,653.

This invention relates to drain fixtures for tubs, basins, sinks, and the like.

It contemplates more especially the provision of instrumentalities for controlling 5 the discharge of waste by mechanical valve lifting means so arranged as to permit lateral as well as longitudinal movement of the lifting rod.

In the installation of drain fixtures considerable difficulty has been encountered in 10 aligning the lifting rod with the discharge valve, and with the usual arrangement of parts the valve mechanism would stick or become jammed within its housing whenever 15 the rod and valve were not in exact alignment.

One object of the present invention is to 20 overcome the difficulties now experienced by providing simple means for insuring the successful operation of the drain valve even if the lifting rod and the valve are not in exact alignment. This is accomplished by 25 the provision of a simple flexible joint preferably a universal joint intermediate the lifting rod and the valve so as to allow for any accidental deviation in the longitudinal axial relation of the rod and the valve, such as may and does occur in its installation.

A further object is to provide means in 30 connection with the overflow pipe from which the valve lifting rod extends for permitting lateral displacement of the rod, and also for automatically keeping the pipe closed so as to prevent any foreign matter 35 from falling into said overflow pipe.

Other objects and advantages will appear 40 from the following description of an illustrative embodiment of the present invention.

To more fully comprehend the invention, 45 reference is directed to the accompanying drawing, wherein:—

Figure 1 is a sectional view of a drain fixture constructed in accordance with the present invention, the fixture being shown 45 in connection with the usual bath-tub.

Fig. 2 is an enlarged perspective view of the universal joint shown in Figure 1.

Fig. 3 is an enlarged perspective view of the overflow pipe closure shown in Figure 1. 50 The fixture selected for illustration is shown attached to the usual bath-tub 10, and comprises a casing 11 surrounding a drain tube 12 both communicating with a discharge or soil pipe 13 through the usual

T-fitting 14. An elbow 15 is disposed from 55 the bottom and one end of the tub and is adapted to register with both the overflow opening 16 and the soil pipe 13 by virtue of the T-fitting 14 above referred to. This arrangement affords a water flow from the 60 basin directly to the soil pipe 13, or up through the usual casing 11, around and down tube 12, through the hollow valve 17 and into the usual soil pipe 13 by virtue of the passage 18 which communicates with 65 the valve seat 22 in the T-fitting 14.

The casing 11 in this instance extends 70 vertically and in axial relation to the soil pipe 13 and both are removed sufficiently from the basin in order to permit them to be encased in the wall of the room to which the basin or tub is attached. This casing 11 is in threaded engagement with the T-fitting or housing 14 at the outlet 18 and holds 75 within it the drain tube 12. The longitudinal axis of the drain tube 12 and the casing 11 coincide so that there is sufficient space for the water to pass around the tube 12 from the opening 19 of the housing 14. To insure this exact central relation and to 80 keep the drain tube 12 always concentric to the casing 11, the extremities of the tube 12 are provided with integral lugs 20 which are spaced at an angular distance of 90 85 degrees with respect to each other. The water is free to flow upwardly between the lugs which occupy very little space within the pipe.

Extending from the lower extremity of 90 the drain tube 12, is the hollow valve 17 which has its ends converging at 21 so as to define bearing faces similar in contour to the face of the valve seat 22. The converging faces 21 are symmetrically arranged with respect to the valve body 17 so that when one end becomes worn it may be reversed; thus giving the valve a duplex bearing surface which adds to its utility. The ends 21 are threaded so that the valve can be readily reversed on the extremity of the drain 95 tube 12.

A flexible joint is inserted intermediate 100 the lifting rod 23 and the drain tube 12 so that the satisfactory operation and reciprocation of the valve 17 does not depend upon the alignment of the rod with the valve mechanism, but permits some deviation of the rod without impairing the successful

operation of the valve. The preferred embodiment of the flexible connection is a simple universal joint (see Figure 2) which comprises a block 24 having communicating holes 25 therethrough on each of its four sides. Retaining loops 26 oppositely disposed with respect to each other pass through the holes 25, and serve as connectors for the drain tube 12 and the crank arm 27 which in turn is actuated by the usual lever not shown. This flexible connection should be such as to withstand tensile and compressive reactions. The lifting rod 23 may be hinged at 28 to another rod 29 in order to insure greater flexibility.

The fact that the rod 23 must be free to move laterally in the event that it is not in exact alignment with the axis the drain tube and valve necessitates the large opening 30 in the cap 31 which acts as a closure for the casing 11; however, it is desirable and necessary to prevent any foreign matter from finding its way into the casing 11, since this would tend to clog or cause unusual wear on the moving parts housed therein. Accordingly a cap or washer 32 is superimposed on the threaded cap 31 and is provided with a hole 33 just large enough to receive the rod 23. The washer 32 slides freely over the cap 31 as the rod 23 moves laterally, and as apparent from the drawing, the washer is large enough to cover the

opening 30 regardless of its position thereon.

Various changes may be made in the embodiment of the invention hereinabove specifically described, without departing from or sacrificing any of the advantages of the invention as defined in the appended claims.

I claim:

1. In a drain fixture the combination of a casing, a drain tube reciprocable therein, guide lugs on said tube, engageable with the inner walls of said casing, a hollow valve secured to one extremity of said tube, a rod projecting from said casing and secured to said tube to effect reciprocation thereof, a universal joint associated with said rod to permit lateral movement thereof, and a closure for said casing automatically adjustable to permit lateral movement of said rod.

2. In a drain fixture the combination of an overflow passage, a drain passage, a valve to control the flow through the drain passage, means to actuate said valve, and a closure for the upper end of said overflow passage comprising a cap threaded to the casing, said cap having a hole in its flat surface, and a washer slidable over said hole and provided with an opening to receive the valve actuating means.

In witness whereof, I hereunto subscribe my name this 23 day of September, 1925.

ROBERT C. ZANNOH.
